J. H. HICKEY

FUSE

Filed July 11, 1923

Fig. 1.

Fig. 2.

Fig. 3.

Inventor:

JOHN H. HICKEY

Arthur L. Sles
ATTY.

UNITED STATES PATENT OFFICE.

JOHN H. HICKEY, OF SAN FRANCISCO, CALIFORNIA.

FUSE.

Application filed July 11, 1923. Serial No. 650,902.

To all whom it may concern:

Be it known that I, JOHN H. HICKEY, a citizen of the United States, residing in the city and county of San Francisco, and State 5 of California, have invented a new and useful Improvement in a Fuse, of which the following is a specification.

My invention relates to improvements in fuses, wherein an articulate conductor is 10 provided with segments having semispherical contacting ends which operate in conjunction with a fusible material to provide continuity of said conductor and to separate the said segments when said fusible material is melted.

The primary object of the present invention is to provide a new and improved fuse for electrical circuits and the like.

Another object of the invention is to provide 20 a new and improved fuse of the character described having improved facilities for providing a positive separation of the fuse at a predetermined temperature.

Another object of the invention is to provide 25 a renewable fuse wherein the conductor may be easily and inexpensively replaced.

I accomplish these and other objects by means of the preferred form of the invention disclosed in the drawings forming a 30 part of the present specification wherein like characters of reference are used to designate similar parts throughout the said specification and drawings, and in which—

Fig. 1 is a longitudinal sectional view, 35 with some of the parts partly broken, of my improved fuse;

Fig. 2 is an elevation of the same disclosing the conductor separated or interrupted; and

Fig. 3 is a transverse sectional view of Fig. 2.

Referring to the drawings, the numeral 1 is used to designate a cylindrical container, preferably of glass or some other suitable 45 transparent material, having an enlarged central portion 2 and open ends;

A metallic cap 3 is detachably mounted upon each end of the container 1 and is provided with an inwardly projecting screw 4, 50 the purpose of which will hereinafter be more fully set forth.

An articulate conductor 6 comprises segments 7 having their contacting ends formed semi-spherical as at 8, said contacting 55 ends being held in position to preserve the continuity of said conductor 6 by means of

a suitable fusible material 9 as disclosed in Fig. 1 of the drawings.

The end segment of the conductor 6 is provided with internally threaded apertures 60 arranged to be engaged by the threaded screws 4 whereby said conductor 6 is held centrally of the container 1.

When the fusible material 9 is melted by the action of heat at a predetermined temperature the contacting semi-spherical ends 8 of the segments 7 will readily permit a positive and complete separation of the said segments 7 and the central segment 7 will fall to one side of the enlarged central portion 2 of the container 1 thereby effecting a positive and complete separation of the segments whereby a flow of current through the fuse will be prevented.

In renewing a fuse by replacing a new 75 conductor, the caps 3 are removed and a new conductor 6 is screwed onto one of the threaded screws 4 in the cap 3. The assembled conductor is then replaced within the container 1 by inserting the same therein 80 and attaching the attached cap 3 to one of the open ends of the container 1. This will bring the unattached end of the conductor 6 into a central position in the opposite open end of the said container 1 where it may be 85 readily engaged by the screw 4 of the remaining cap 3 and thereby held in operative position.

It is obvious from the foregoing that I have provided a new and improved fuse 90 wherein improved facilities are provided for a positive separation of a conductor when the fuse is blown, and also improved facilities for renewing the conductor easily and inexpensively.

Having thus described my invention what I claim as new and desire to secure by Letters Patent is—

1. A fuse comprising an articulate conductor having segments provided with 100 semi-spherical ends; and a fusible material connecting said semi-spherical ends of said segments whereby the same may be separated when said fusible material is melted.

2. A fuse comprising a container having 105 an enlarged central portion; an articulate conductor having segments provided with semi-spherical ends; a fusible material connecting the semi-spherical ends of said segments whereby the same may be separated 110 when said material is melted.

3. A fuse comprising a container having

an enlarged central portion and also having open ends; a metallic cap mounted upon each open end of said container; an articulate conductor detachably connected at the 5 ends thereof to said caps and provided with segments having semi-spherical contacting ends; and a fusible material connecting said semi-spherical ends whereby said segments may be separated when said fusible material is melted.

4. A fuse comprising a cylindrical container having an enlarged central portion and open ends; metallic caps detachably

mounted upon the open ends of said container; an articulate conductor mounted 15 centrally of the container and having segments whose outer ends are screw threaded to the caps and whose intermediate contacting ends are semi-spherical; and a fusible material connecting the contacting 20 semi-spherical ends whereby said segments may be separated when said fusible material is melted.

In witness whereof I hereunto set my signature.

JOHN H. HICKEY
